DESIGN FOR A PORTABLE AIR COMPRESSOR

Adelbert C. Radtke, Forest Park, and Neil B. Spurgeon, River Forest, Ill., assignors to Sears, Roebuck and Co., Chicago, Ill., a corporation of New York

Application October 3, 1938, Serial No. 80,222

Term of patent 14 years

To all whom it may concern:

Be it known that we, Adelbert C. Radtke and Neil B. Spurgeon, citizens of the United States, residing at Forest Park and River Forest, respectively, in the county of Cook and State of Illinois, have invented a new, original, and ornamental Design for a Portable Air Compressor, of which the following is a specification, reference being had to the accompanying drawing, forming a part thereof.

Fig. 1 is a perspective view of a portable air compressor embodying our invention.

Figs. 2 and 3 are front and rear views of the same respectively.

The side of the device not seen in the drawing is substantially similar to the side which is shown.

We claim:

The ornamental design for a portable air compressor, substantially as shown and described.

ADELBERT C. RADTKE.
